DESIGN FOR A RANGE

Joshua Gordon Lippincott, Scarsdale, N. Y., assignor to Florence Stove Company, Gardner, Mass., a corporation of Massachusetts

Application August 10, 1944, Serial No. 114,814

Term of patent 14 years

(Cl. D81—4)

To all whom it may concern:

Be it known that Joshua Gordon Lippincott, a citizen of the United States, residing at Scarsdale, in the county of Westchester and State of New York, has invented a new, original, and ornamental Design for a Range, of which the following is a specification, reference being had to the accompanying drawing, forming part thereof.

The figure is a perspective view of a range, showing my new design.

The other end of the range is substantially like the end shown.

I claim:

The ornamental design for a range, as shown and described.

JOSHUA GORDON LIPPINCOTT.
